United States Patent Office.

ANDREW J. CRONK OF PEORIA, ILLINOIS.

Letters Patent No. 67,507, dated August 6, 1867.

IMPROVED PAD-TREE.

The Schedule referred to in these Letters Patent and making part of the same.

TO ALL WHOM IT MAY CONCERN:

Be it known that I, ANDREW J. CRONK, of the city and county of Peoria, have invented a new and improved Pad-Tree; and I do hereby declare that the following is a full, clear, and exact description of the construction and operation of the same, reference being had to the accompanying drawings, making a part of this specification, in which—

Figure 1 is a top view of my improved pad-tree.

Figure 2, a side view.

Figure 3, vertical section of a part of the tree, as indicated by the line M—N in fig. 1.

Like letters in the different figures of the drawings indicate like parts.

The nature of my invention consists in the peculiar construction of a pad-iron provided with nuts or burs, and combined with the bridge by means of screws and the terrets, to give greater strength and solidity to the tree; also constructing the D's on the ends of the bridge to receive the back-straps, instead of on the pad-iron, as heretofore, to sustain in a more substantial and durable manner the weight of the shafts.

To enable any one skilled in the art to make and use my invention, I will proceed to describe its construction and operation.

A is the pad-iron, cast with burs or nuts *a a*, B the bridge or bow, C C the D's for back-straps, D D the terrets, E E the screws. The burs of the pad-iron are provided with screw-threads properly constructed within them in the casting. The bridge is made in the usual form, except that their ends are constructed with D's. The terrets are as ordinarily. A padding of leather, F F, is suitably secured around the iron, and compacted between the burs even with their top edges. (See figs. 2 and 3.) Suitable springs may be used in connection with the padding, if desired. The bridge is secured to the irons in the pads by the terrets, and screws being introduced through holes in the same and screwed into the burs until the bridge is made fast to the irons, (see figs. 2 and 3,) thus forming a complete and solid pad-tree. As heretofore remarked, the D's for the back-straps are generally constructed on the ends of the pad-irons, which, being of a thin plate form, and the manner in which they are connected with the bridge, are not likely to be as strong as on the ends of the bridge for sustaining the weight of the shafts. The tree is only stationary between the terrets, and by a proper adjustment of the padding around the irons can be generally made to fit the back of any horse.

Having thus fully described my invention, what I claim therein as new, and desire to secure by Letters Patent, is—

1. The pad-iron, as constructed and combined with the bridge, substantially in the manner and for the purpose as herein set forth.
2. The bridge, constructed with D's and combined with the pad-iron, substantially in the manner and for the purpose as herein set forth.

ANDREW J. CRONK.
